FLOAT VALVE WITH AIR CUT-OFF

Gerald E. White, 121 SE. 12th St., Pompano Beach, Fla.
Filed Dec. 12, 1962, Ser. No. 244,050
4 Claims. (Cl. 137—391)

This invention relates to the construction of valves used to control the liquid level in a tank. Float-operated devices are well known in this field, and this invention is associated with such a mechanism. Water-softening equipment commonly presents the problem of establishing a maximum water level in a brine tank, while permitting the brine to be withdrawn under vacuum conditions. If the brine is withdrawn to the point that the level reaches the port of the control valve, continued suction will pull air into the line. This is not only undesirable in itself, but causes oxidation of the iron ions associated with the mass of water-softening material. The oxidized ion becomes a precipitate, and presents a flushing problem. It is desirable to cut off the flow out of the brine tank before the liquid level falls below the valve port, and thus eliminate the oxidation. The control valve should therefore establish both a maximum and a minimum liquid level. A device for performing this general function is shown in the United States Patent No. 2,716,422.

The present invention provides the general double-valve function in a structure that maintains positive float and valve alignment, and is readily adaptable to the molding of many of the components in plastic materials. The several features of the invention will be analyzed in further detail through a discussion of the particular embodiment illustrated in the accompanying drawings. In the drawings:

FIGURE 1 is a sectional elevation of a conventional brine tank controlled by a valve embodying the present invention, the valve being in position to stop further flow into the tank.

FIGURE 2 is a sectional elevation of the valve mechanism alone, on a somewhat enlarged scale over that of FIGURE 1, illustrating the valve in an intermediate position as the liquid is being withdrawn from the tank under vacuum conditions in the water softener.

FIGURE 3 is a section on the same mechanism shown in FIGURE 2, showing the position of the valve for blocking further flow out of the tank, and thus establishing the minimum liquid level.

FIGURE 4 is a perspective view showing the valve assembly in the FIGURE 1 position.

Referring to FIGURE 1, the brine tank 10 is provided with a cover 11, and with a wooden structure 12 functioning as a platform to support the salt blocks 13 and 14 at a predetermined distance from the bottom 15 of the tank. For most efficient operation of the system, the distance of the liquid level 16 above the top of the platform structure 12 should be held to a minimum, thus exposing a uniform face of the salt block to the incoming fresh water for generation of the brine. The drawing shows considerably more exposure to the salt block than is recommended, and is exaggerated for purposes of illustration. After the liquid in the tank has been exposed to the salt block for a comparatively short time, a brine solution is produced which is withdrawn during the regeneration cycle of the water-softener system. The subjection of the mass of ion exchange material in the water softener to the flow of brine will prepare the mass for a further period of normal functioning. The conduit 17 leads from the control valve mechanism generally indicated at 18 to the water softening device (not shown), which forms no part of the present invention.

The valve mechanism 18 is surrounded by a protective housing 19 having openings as shown at 20 and 21 in

2

FIGURE 1 communicating with the interior of the tank 10. A base 22 is preferably provided with a flange 23 adjacent the periphery for locating the housing 19 with respect to the valve structure. The flange 23 may either be molded integrally with the base 22, or secured to it. The base 22 is also provided with a central boss 24 for engaging and positioning the body 25 of the valve. A chamber 26 is defined by the valve body 25, and communicates with the conduit 17 at the connection 27. A passage 28 extends upwardly from the chamber 26, and may be blocked by the valve member 29 carried on the rod 30. A conical guiding member 31 provides for the alignment of the valve member 29 with respect to the lower extremity of the passage 28. A bearing portion 32 at the upper extremity of the body 25 slidably receives the rod 30, and maintains the axial alignment of it with respect to the assembly. Liquid moving to and from the chamber 26 will traverse the passage 28, and the radially-extending ports 33, which are disposed above the shoulder 34. This shoulder is preferably provided by a gasket supported by an offset in the body portion 25 of the valve.

In the position shown in FIGURE 1, the liquid level 16 has risen to the permitted maximum. The float 35 has a central portion 36 providing a recess 37 which is disposed to receive the bearing portion 32 of the body of the valve when the float is in the extreme down position shown in FIGURE 3. The conical exterior surface of the bearing portion 32 facilitates the entry into the recess 37. The central portion 36 of the float also contains a bearing portion 38 for slidably receiving the valve rod 30. An end-fitting 39 has preferably threaded engagement with the end of the rod 30, and provides a limit to the sliding movement of the float with respect to the rod. The result is a lost-motion connection permitting considerably more vertical movement of the float than the rod 30 is capable of. A tubular housing 40 is engaged with the bearing section 38 to seal off the interior of the float 35, and a cap 41 is preferably sealed to the end of the housing to complete the closure. A seal at the juncture of the tubular housing 40 with the top 42 of the float is also recommended.

As the liquid is progressively withdrawn from the tank 10, the float 35 moves downward through the intermediate position shown in FIGURE 2 to the lower position shown in FIGURE 3. At this time, the annular ridge 43 at the lower extremity of the float contacts the shoulder 34 to create a seal. Continued application of suction in the line 17 will produce increased pressure at the shoulder 34, and this arrangement has the effect of closing off the flow moving through the radial ports 33. The lost-motion connection referred to above will permit the float to move down into the FIGURE 3 position, with the end-fitting 39 moving up into the space defined by the tubular housing 40. The liquid level 16 is still above the ports 33 in the FIGURE 3 position, thereby preventing the ingress of air into the line 17.

The particular embodiments of the present invention which have been illustrated and discussed herein are for illustrative purposes only and are not to be considered as a limitation upon the scope of the appended claims. In these claims, it is my intent to claim the entire invention disclosed herein, except as I am limited by the prior art.

I claim:

1. A valve mechanism, comprising:
a body portion having an inlet communicating with a chamber, and having a normally vertical passage in the top of said chamber, said body portion having an extension tapering upward to reduced diameter surrounding said passage and an external shoulder surrounding said extension, and also having radial

ports disposed above said exterior shoulder communicating with said passage,
a rod slidably mounted in said extension, and having a valve member disposed in said chamber and engageable with said body portion to block the opening, 5
said extension maintaining said rod in axial alignment therewith,

a stop at the upper extremity of said rod, and
a float slidably mounted on said rod above said body portion, said float having a recess in the bottom thereof for receiving said extension, said exterior shoulder including a gasket engageable with the underside of said float to seal off said ports on lowering said float. 10

2. A valve mechanism, comprising: 15
a body portion having an inlet communicating with a chamber, and having a normally vertical passage in the top of said chamber, said body portion having an extension tapering upward to reduced diameter surrounding said passage and an external shoulder 20 surrounding said extension, and also having radial ports disposed above said exterior shoulder communicating with said passage,
a rod slidably mounted in said extension, and having a valve member disposed in said chamber and engageable with said body portion to block the opening in said passage, said extension maintaining said rod in axial alignment therewith, and 25
a float slidably mounted on said rod for limited movement with respect thereto above said body portion, said float having a recess in the bottom thereof for receiving said extension, said exterior shoulder including a gasket engageable with the underside of said float to seal off said ports on lowering said float. 30

3. A valve mechanism, comprising: 35
a body portion having an inlet communicating with a chamber, and having a normally vertical passage in the top of said chamber, said body portion having an extension surrounding said passage and an external shoulder surrounding said extension, and also 40

having ports disposed above said exterior shoulder communicating with said passage,
a rod slidably mounted in said extension, and having a valve member disposed in said chamber and engageable with said body portion to block the opening in said passage, said extension maintaining said rod in axial alignment therewith, and
a float slidably mounted on said rod for limited movement with respect thereto above said body portion, said float having a recess in the bottom thereof for receiving said extension, said exterior shoulder including a gasket engageable with the underside of said float to seal off said ports on lowering said float.

4. A valve mechanism, comprising:
a body portion having an inlet communicating with a chamber, and having a normally vertical passage in the top of said chamber, said body portion having an extension surrounding said passage and an external shoulder surrounding said extension, and also having ports disposed above said exterior shoulder communicating with said passage,
a rod slidably mounted in said extension, and having a valve member disposed in said chamber and engageable with said body portion to block the opening in said passage, said extension maintaining said rod in axial alignment therewith, and
a float secured to said rod above said body portion, said float having a recess in the bottom thereof for receiving said extension, a portion of said float being engageable with said shoulder to block flow through said ports.
